GROUND INSERTED CEMETERY VASE

Lloyd E. Magers, Chicago, Ill.

Application April 1, 1949, Serial No. 84,953

5 Claims. (Cl. 47—41)

1

This invention relates to a vase, and more particularly to a combined marker and container which retains water when opened, is self-draining when closed, and is easily drilled into the ground to display and moisten flowers and the like in cemeteries, lawns, and the like.

Heretofore, vases used in cemeteries have been subject to certain disadvantages. For example, loose vases are easily lost or broken, and are unsightly when empty. Partially buried or anchored vases are not particularly advantageous even when buried substantially flush with the ground level, because they will retain water which will become stagnant in warm weather and will freeze in cold weather, thereby cracking the vase. Further, expansion of the ground due to frost will loosen and raise the vase. Since such partially buried vases could only be drained by removal from the ground, and since winter frost has a raising effect thereon, they soon become loosely anchored and lose their status as a permanent fixture.

The aforementioned disadvantages will be more frequently encountered in the future in the use of the vases heretofore known in the art insofar as it is the present trend in cemetery management to dispense with monuments, above the ground receptacles or stands, and the like, thus making it necessary to more frequently use flower vases or receptacles which may be imbedded in the ground with the top flush with the top of the earth.

It is a feature of the instant invention to provide a permanent grave marker vase which comprises a metallic tube of brass or other material which will resist deterioration due to the natural moisture and mineral content in the ground. One end of the tube is preferably toothed to facilitate boring a hole in the ground for inserting the tube. A disk plate is welded across the tube intermediate the ends thereof and this plate has a drain hole therethrough. The plate is preferably inclined to facilitate drainage to the drain hole. The open top end of the tube carries a hinged cover composed of heavy cast bronze or the like weather-resisting material, arranged to receive an engraved identification or marker plate on the top thereof. A valve is positioned under the disk to close the drain opening therein and a rod extends through this opening to the top of the tube where it passes through a guide bracket. The plate divides the tube into a top water compartment and an open-bottomed drain compartment which not only receives water from the top compartment but

2

also is adapted to receive earth in the event of frost expansion thereby preventing frost raising of the tube out of the ground.

A coil spring urges the rod upwardly to seat the valve against the drain opening in the bottom of the plate, thereby closing the same. When the cover is opened, the valve will be closed and the tube can be filled with water for sustaining the life of cut flowers. When the cover is closed, it depresses the spring-urged rod and the valve will be automatically unseated and water in the top portion of the tube will drain through the drain hole into the bottom chamber of the tube and on into the soil. A perforated strainer plate is disposed about the valve rod to prevent entrapment of foreign material between the drain hole and the valve head.

The tube is inserted in the ground so that the cover, when closed, will be substantially flush with the surrounding earth or cut grass level, permitting grass mowing machines and the like to pass freely thereover. In closed position of the cover, the engraved identification plate secured to the top surface of the cover will be in an easily readable substantially horizontal position, while in the open position of the cover the plate will be in an easily readable substantially vertical position.

Accordingly, it is an object of this invention to provide an improved flower vase and grave marker.

Another object of this invention is to provide a flower vase which may be inserted in the ground and left in such a position the year round without appreciable deterioration.

Another object of this invention is to provide a flower vase which lends itself to be easily inserted in the ground and which provides selectively operable draining facilities for the water within the vase.

Another important object of this invention is to provide a flower vase which may be permanently inserted in the ground having its top flush with the earth and having a cover that will serve as an identification marker for the plot.

A further object is to provide a receptacle for insertion in the ground and having a top water compartment and an open-bottomed drain compartment which will also receive earth as it swells in freezing weather, thereby preventing frost from raising the receptacle above the ground level.

The specific nature of the invention, as well as other objects and features thereof, will become apparent to those skilled in the art from the fol-

lowing detailed description of the annexed sheet of drawings which, by way of preferred example only, illustrates one specific embodiment of the invention.

On the drawings:

Figure 1 is a top plan view, showing the cover in closed position, of a vase having the features of this invention;

Figure 2 is a vertical cross-sectional view of the vase of Figure 1 taken substantially along line II-II of Figure 1, and which shows the cover in closed position with the valve unseated to drain the water chamber of the vase;

Figure 3 is a vertical cross-sectional view similar to Figure 2, but showing the cover in open position with the valve seated to close the drain hole so that the upper chamber of the vase may receive cut flowers and water; and

Figure 4 is a fragmentary horizontal cross-sectional view taken substantially as indicated by the line IV-IV on Figure 3 and which shows the valve rod in cross-section and the perforated strainer plate over the drain hole.

As shown on the drawing:

In the various figures on the drawing, numeral 10 indicates generally a vase constructed in accordance with this invention. Tube 12 of brass or other water and mineral resistant metal, which may be readily and economically formed in a drawing or forming process, comprises a casing for the vase 10. One end of the open ended tube 12 preferably has the integrally formed teeth 12a which greatly facilitate the digging or boring of a hole in the soil for the insertion of the vase 10. As shown in Figure 2, a pair of diametrically opposite teeth 12a can be lanced and bent outwardly as at 12a' to form locking tangs which will better anchor the vase in the ground.

An inclined disk plate 14 is welded to the inner surface of the tube 12 at a location 12b near the mid-section of the tube 12. This plate, as shown in Figures 2 and 3, is inclined or pitched toward a drain hole 14a in the plate. The top of tube 12 is closed by cover 16. The cover 16 has a bifurcated hinge portion 16a with an aperture therethrough to accommodate a hinge pin 18 which is carried by a lug 20 secured as by rivets 22 to the tube 12 adjacent the top end thereof.

Figure 2 shows the cover 16 in closed position and Figure 3 shows the cover 16 in open position. It will be noted that cover 16 has an annular seat 16b which seats on the top end of the tube 12. It will be further noted that the cover opens in alligator fashion about the axis of the hinge pin 18. The cover 16 in open position rests with the top surface adjacent the projection 20a on the lug 20. The cover 16 has a weighted portion 16c remote from the hinge pin 18 so as to maintain the cover 16 in closed position due to its weight.

An appropriately engraved identification plate 24 (Figure 1) may be secured to the curved top of the cover as by screws or rivets 26. The identification plate 24 is preferably inserted within a recess 16d on the top surface of the cover 16 so that the top of the identification plate will be flush with the top surface of the cover.

The drain hole or aperture 14a in the plate 12 is selectively opened or closed by a spring biased valve 28 of rubber or other resilient material. A valve rod or arm 30 protrudes upwardly from the valve 28 which in closed position seats on the under surface of the disk plate 14 closing the aperture 14a. The valve rod 30 is supported and

guided in upright position by a guide bracket 32 which slidably embraces the rod 30 at a point remote from the valve 28. The bracket 32 is secured to the inner surface of the tube 12 by the same rivets 22 which secure the hinge lug 20. A compression spring 34 loosely embraces the rod 30 and is bottomed on the bracket 32. A cotter pin 36 is inserted through a suitable opening in the valve rod 30 adjacent the top end thereof to arrest free expansion of the spring 34.

A protuberance 16e of the cover 16 extends downwardly when the cover 16 is closed and strikes the top of the valve rod 30 to shift the valve rod and valve 28 downwardly so as to unseat the valve 28 from the drain opening 14a in the disk plate 14. As seen in Figure 2, this further compresses the spring 34 between the bracket 32 and the cotter pin 36, and this compression is easily accommodated by the weight of the cover 16 with the aid of the added weighted cover portion 16c acting through a long lever arm from a fulcrum about the axis of the hinge pin 18.

The disk plate 14 is preferably normal to the axis of the valve rod 30 so that the rubber or plastic valve head 28 will have a circular ring seating contact with the rim of the drain hole 14a.

When the cover 16 is opened, load on top of the guide rod 30 is released, allowing the spring 34 to expand against the cotter pin 36 moving the guide rod 30 axially upwardly so that the valve 28 closes the drain aperture 14a in disk plate 14, as shown in Figure 3. A strainer disk 38 is loosely disposed on the rod 30 above the plate 14. This disk 38 has perforations 38a therethrough and when the cover 16 is in closed position, as shown in Figure 2, and the valve 28 is unseated, the rod 30 guides the disk to rest over the drain opening 14a. The perforations 38a then permit water to drain therethrough into the cavity below the plate 14. When the cover is opened and the valve 28 is moved upwardly to seat against and close the drain opening 14a, the valve will raise the disk sieve 38 off of the plate 14 so that any stems or other debris extending partly through the disk will not interfere with a full seating of the valve.

From the foregoing description it is to be understood that I have a vase of metallic structure having a partitioned tube-like casing, the lower end of which is toothed to facilitate the digging or boring a hole in the soil for inserting the vase. As illustrated in Figure 2, the case is inserted in the ground with the top end of the tube being substantially flush with the top of the earth, the part of the tube below the partition being free of soil to accommodate water from the top compartment as well as expanding earth from beneath the tube which might otherwise tend to raise the tube. The cover of the vase may be opened and in so doing the partition is sealed so that the upper section of the tube may act as a vessel to receive water and cut flowers. When the flowers are removed, it is not necessary to remove the vase from the ground to empty the water therefrom. It is only necessary that the cover be closed and by so doing the drain opening in the partition is uncovered so that water may drain from the vessel part of the tube into the soil at the bottom of the lower end of the tube. The covered vase so left in the ground provides an identification marker for a cemetery plot or the like.

It will be further understood that various de-

tails of construction may be varied through a wide range without departing from the principles of this invention and it is, therefore, not the purpose to limit the patent granted hereon otherwise than necessitated by the scope of the appended claims.

I claim as my invention:

1. A receptacle of the type suitable to be permanently inserted in soil comprising an open ended casing having teeth on the bottom end thereof, a hinged cover for the top of said casing, an apertured partition member spaced between said open ends of said casing and dividing the casing into top and bottom compartments, means on said casing defining a valve guide, valve means disposed in said casing for selectively opening or closing the aperture in said partition member, said valve means being associated with the valve guide to accommodate opening and closing movements of said valve means, and means on said cover for urging said valve means to open position when said cover is closed.

2. A receptacle of the type suitable to be permanently inserted in soil comprising an open ended casing, a cover member hinged to said casing for closing one end thereof, an apertured partition member traversing said casing intermediate the length thereof, resiliently urged valve means disposed in said casing for selectively opening or closing said aperture, means on said casing defining a guide bracket, a valve rod shiftably embraced by said bracket and actuated by said cover to open the valve when the cover is closed.

3. A receptacle suitable to be permanently inserted in soil comprising an open ended tube, a cover hinged on one end of the tube to selectively close said end, a plurality of teeth on the other end of the tube, a partition member transversely secured to said casing in spaced relation to the ends thereof, said partition member having a drain port therein, a plug beneath said member for controlling said port, a rod extending from said plug to the top of the tube, resilient means urging said rod to move the plug against the port, said cover having a depending lug for actuating said rod to open the port when said cover is closed, a perforated plate on said rod above said member for overlying said port when the port

is open, and means for lifting the plate off of the member when the port is closed to insure full seating of the plug in the port.

4. A vase suitable to be permanently inserted in soil comprising an open ended casing, a cover member hinged to said casing for closing the top end thereof, a plurality of teeth on the bottom of the casing to facilitate the digging of a suitable hole in the soil, an apertured partition member transversely disposed in said casing in spaced relation to said ends, a check valve for selectively opening or closing said aperture, resilient means urging said valve to said closed position, means on said cover defining a striker for urging said valve to open position when said cover is closed, means on said cover defining a weighted lever for maintaining said cover in said closed position and said valve in said open position, a sieve defining water passages therethrough for covering said aperture when said valve is in open position, and means on said cover for accommodating an identification plate on the top surface thereof.

5. A cemetery grave marker and vase comprising a cylindrical casing having top and bottom compartments connected by a drain port, said bottom compartment having an open bottom, a heavy cover pivoted on the top end of the casing, marker means on the top of the cover, a spring loaded valve controlling the drain port, valve guide means secured to said casing, and a valve actuator cooperating with said valve guide means and adapted to be depressed by closing movement of the cover to open the valve.
